INFANT'S CRIB

Earl F. Hamilton, Columbus, Ind., assignor to Hamilton Cosco, Inc., Columbus, Ind., a corporation of Indiana
Filed Jan. 14, 1960, Ser. No. 2,425
9 Claims. (Cl. 5—100)

This invention relates to an infant's crib, and more particularly to a crib having collapsible sidewalls.

It is an object of my invention to provide a crib of attractive appearance which can be simply and economically manufactured largely from metal-tubing, which can be shipped in knocked-down condition, and which will be sturdy and rigid when erected. It is a further object of my invention to provide an infant's crib having collapsible sidewalls which can be easily moved to and from a collapsed position in which they are disposed in a general plane of a mattress supported on said crib.

In accordance with my invention, there is provided a spring-supporting frame rigidly connected at each of its ends to a pair of opposed end boards extending substantially above the plane of the frame and thus closing the ends of the crib. Said frame and end boards are supported on a plurality of ground-engageable legs.

The sides of the crib are enclosed by a pair of collapsible sidewalls mounted on the pair of end boards. Each of said sidewalls comprises a pair of rigid frame members supporting a sheet of fabric material and pivotally connected along a horizontal axis. The lower of said pair of frames is retained in a fixed vertical plane with respect to the end boards, and the upper of said pair of frames is swingable about its pivotal connection to the lower frame for movement between a sidewall erected position in which its horizontally extending upper end is generally coplanar with the upper ends of the end boards and a sidewall collapsed position in which said upper end is generally coplanar with said spring-supporting frame. Conveniently, means are provided on said end boards for releasably locking said upper sidewall frame in sidewall-erected position.

Other features and embodiments of my invention will become apparent from the more detailed description which follows and from the accompanying drawings, in which:

FIG. 1 is a perspective view of an infant's crib embodying my invention, and showing its sidewalls in erected and collapsed positions;

FIG. 2 is a side elevation in partial section of one of the sidewalls and showing its connections to the end boards;

FIG. 3 is a front elevation of the inwardly presented face of one of the end boards;

FIG. 4 is an enlarged fragmentary perspective view of the spring-supporting frame-end board mounting;

FIG. 5 is a front view of one of the sidewall locks; and

FIG. 6 is a side view of the lock shown in FIG. 5.

As illustrated in the drawings, my crib is provided with a generally rectangular spring-supporting frame 10 conveniently formed from lengths of metal-tubing. As shown in FIG. 4, the inner faces of the side members 12 of the frame 10 are slotted adjacent their ends for the reception of offset tongues 14 formed at the ends of the end members 16 of said frame to thus hold said end and side members connected. The ends of the tongues are offset downwardly at about a 45° angle whereby upon insertion into the side members 12, the tongues will hold said side members rigid and keep them from twisting when the springs are mounted on the frame. Conveniently, a plurality of openings 18 are formed in each of the side and end members 12 and 16 respectively for mounting a set of springs thereon.

2

The opposed ends of the spring-supporting frame 10 are rigidly connected to a pair of end boards 20 which project slightly below, and substantially above, the plane of said frame. As shown in FIG. 2, each of the end boards 20 comprises a pair of lengths of metal-tubing bent into a generally U-shape and rigidly interconnected as by sleeves 22 to thus form a rigid peripherally extending end board frame 24. As shown in FIG. 4, a plurality of slots 26 are formed in each of the frames 24 for the reception of lugs 28 projecting outwardly from a rigid panel 30, conveniently formed of Masonite or the like. Desirably, the inwardly presented faces of the panels 30 may be covered with a pad 32 retained thereon by a fabric skin 34 encapsulating the panel 30 and the pad 32. Conveniently, in order to enhance the attractive appearance of the end boards, the encapsulating skins 34 extend over the entire surface of the panel 30 and pad 32 including the lugs 28. In mounting the panels on the frames 24, the sections of said frames are disposed around the panels and then forced inwardly over the lugs 28, said lugs being received in the frame slots 26. This produces a binding interlocking fit between the frames and panels without the necessity of using brackets, clips, etc.

The end boards are connected to the spring-supporting frame 10 by bolts 36 extending through the end board frames 24 and the flattened ends 38 of the side members 12 which project longitudinally outwardly beyond the end members 14 of the frame 10. The end boards 20 and spring-supporting frame 10 are further interconnected and cross-braced by a plurality of ground-engageable legs 40 which extend downwardly from said frame and end boards to thus support the crib in an elevated position. As shown in FIG. 4, each of the legs 40 is conveniently formed from a length of metal-tubing connected at its upper end to one of the side members 12 by a bolt 42. The leg 40 is angled inwardly from its connection to the side member 12 toward the longitudinal axis of the crib, and then downwardly for connection to the lower horizontal stretch of the end board frame 24, by a bolt 44. In this manner, the legs 40 thus serve as a means for supporting the crib and cross-braces for the connections between the end boards and the spring-supporting frame 10.

As best shown in FIG. 2, the sides of the crib are enclosed by a pair of collapsible sidewalls. Each of said sidewalls comprises an upper frame 48 conveniently formed from a length of metal-tubing bent into a generally U-shape and pivotally connected to a lower frame 50 also formed from a length of metal-tubing bent into a generally U-shape. The adjacent ends of the frames 48 and 50 are pivotally connected as by pins 52 to thus permit said frames to be swingable with respect to each other on a horizontal axis. Each pair of upper and lower frames 48 and 50 supports a sheet of flexible fabric netting 54 conveniently mounted on said frames as by a peripheral sleeved hem 56.

To mount each of the sidewalls on the crib, I provide a pair of vertically spaced headed pins 58 on each end of the lower frame 50, said pins being received in slots 60 formed in the inwardly presented faces of the end board frames 24. Conveniently, the slots 60 converge from top to bottom and are formed by slitting the tubing forming the frame 24 and then bending said tubing inwardly to provide a pair of vertically extending ears 62 extending along the opposed sides of each of the slots 60. In this manner, the expanded heads on the pins 58 may be inserted into said slots with the ears 62 retaining said pins in fixed longitudinal position therein but permitting said pins to be vertically slidable in said slots for vertical sliding movement of the frame 50 with respect to the end boards 20.

The upper sidewall frame 48 is also provided with a headed pin 64 projecting outwardly from each of its ends. As shown in FIGS. 5 and 6, each of the pins 64 is receivable in a gravity actuated lock mounted on one of the end board frames 24 adjacent the upper end thereof. Each of said locks comprises a sheet-metal bracket 66 provided with an open-ended vertically extending slot 68 in which one of the pins 64 is received. The frame 24 is recessed, as at 70, in the area behind the slot 68 for the reception of the head on the pin 64. The pin is releasably retained in the slot 68 by a gravity actuated latch 72 swingably mounted on the bracket 66 as by a pivot pin 74. As shown in FIG. 5, the latch 72 is provided with an inwardly presented latch nose 76 engageable with one of the walls of the recess 70 so that upward movement of the pin 64 against the latch 72 will cause said latch to bear against the wall of the recess 70 and thus prevent any further upward movement of the pin 64. However, the latch 72 is swingable outwardly to the dotted line position shown in FIG. 5 to permit the pin 64 to be moved upwardly and out of the slot 68 for unlocking the upper sidewall frame 48 from the end board.

Thus, each of my collapsible sidewalls is movable from its erected position (as shown to the right in FIG. 1) in which the upper and lower frames 48 and 50 lie in the same vertical plane to a collapsed position (as shown to the left in FIG. 1) in which the upper sidewall frame 48 is disposed in the same general horizontal plane as the lower sidewall frame 60. To effect such a collapse, the latches 72 are swung outwardly so that their noses 76 are out of the vertical plane of the pins 64. The frames 48 and 50 are then raised with their pins sliding in the slots 69 and 68 until the pins 64 on the upper frame 48 clear the slots 68 to thus permit the upper frame to be swung downwardly to its fully collapsed position in which its upper horizontally extending stretch lies in the same horizontal plane as the lower stretch on the lower frame 50. Such collapsing movement of the upper frame 48 will thus permit the sidewall netting 54 to be collapsed in the manner shown to the left in FIG. 1 to give access to the crib along the entire length of the crib side.

I claim as my invention:

1. In an infant's crib, a spring-supporting frame mounted on a plurality of ground-engageable legs, a pair of end boards mounted on the opposed ends of said frame and extending substantially thereabove, a pair of collapsible sidewalls mounted on said end boards and extending along the sides of the crib, each of said sidewalls comprising a pair of opposed frames supporting a sheet of fabric netting and pivotally connected at the opposed ends of said sidewalls on a horizontal pivotal axis for moving each of the sidewalls between an erected position in which its upper horizontally extending end is disposed well above the plane of said spring-supporting frame and the netting is taut and a collapsed position in which said upper horizontally extending end is disposed adjacent the plane of said spring-supporting frame and the netting intermediate the pivotally connected ends of said sidewall frames sags downwardly substantially below the plane of said pivotal axis whereby the upwardly presented face of a mattress which may be supported on said spring-supporting frame will be disposed above the plane of a substantial portion of the downwardly sagging netting, and means for releasably locking said sidewalls in erected position.

2. The invention as set forth in claim 1 in which each of said sidewalls comprises upper and lower generally U-shaped frames pivotally connected at their adjacent ends at the opposed ends of the sidewall and supporting said sheet of fabric netting, said lower frame being retained in a fixed vertical plane and said upper frame being swingable between a sidewall erected position in general vertical alignment with the lower frame and a sidewall

collapsed position in which it is generally parallel to the lower frame and in the general horizontal plane thereof.

3. In an infant's crib, a spring-supporting frame mounted on a plurality of ground-engageable legs, a pair of end boards mounted on said frame and extending substantially thereabove, a pair of collapsible sidewalls extending along the sides of the crib, each of said sidewalls comprising a lower generally U-shaped frame having a plurality of outwardly projecting members slidably carried in a plurality of vertically spaced slots formed in the inwardly presented face of each of said end boards along the lateral edges thereof, said lower frame being pivotally connected along a horizontal axis to the opposed ends of an upper generally U-shaped frame having an outwardly projecting member at each of its ends, said slots and the outwardly projecting members on the lower frames limiting the sliding movements of the sidewalls and supporting said sidewalls on the crib, and a sheet of flexible netting mounted on said upper and lower frames, and a plurality of locks mounted on the inner faces of the end boards at the lateral edges thereof and adapted to receive the outwardly projecting members on said upper frames for releasably locking the sidewalls in an erected position, said sidewall frames being vertically slidable in said slots and locks to release said upper frames from the locks for swinging movement into a sidewall collapsed position in which said upper frames are disposed in the general horizontal plane of the lower frames and said flexible netting sheets are collapsed with the major portion of the upwardly presented edges of said netting sheets being disposed substantially below said horizontal axis whereby the upper face of a mattress which may be disposed in said spring-supporting frame will be disposed above the plane of said upwardly presented edges.

4. The invention as set forth in claim 3 with the addition that the outwardly projecting members on said lower frames have expanded heads, and the end boards are provided with peripherally extending frames of metal-tubing with said slots being formed therein, said tubing extending inwardly into the slots along the lateral edges thereof to engage said expanded heads for slidably retaining said members in the slots.

5. The invention as set forth in claim 4 in which the upper ends of said slots have a width greater than the widths of said expanded heads and the lower ends of said slots have a width smaller than the width of the heads.

6. In an infant's crib, a generally rectangular spring-supporting frame, a pair of end boards rigidly mounted on the opposed ends of said frame and extending above and below the plane of said frame, a plurality of ground-engageable legs supporting said crib, the upper end of each of said legs being connected to said frame along one side thereof and to one of the end boards, a pair of collapsible sidewalls mounted on said end boards and extending along the sides of the crib in the vertical planes of the lateral edges of said end boards, each of said sidewalls being collapsible about a horizontal pivotal axis for moving the sidewalls between an erected position in which their upper horizontally extending ends are generally coplanar with the upper ends of the end boards and a collapsed position in which said upper ends are generally coplanar with the spring-supporting frame, and means for releasably locking said sidewalls in erected position.

7. The invention as set forth in claim 6 in which each of the legs is connected to a side of the frame adjacent its connection to an end board and to an end board below the plane of the frame and inwardly from the lateral edge of said end board.

8. The invention as set forth in claim 1 in which each of said end boards comprises a sectioned rigid tubular frame forced inwardly around the peripheral edges of a rigid panel, said panel having a plurality of lugs received in slots formed in the inwardly presented face of said

frame and retained therein by the sectioned frame locked in an inwardly stressed position against said panel.

9. In an infant's crib, a spring-supporting frame carried in an elevated position on a plurality of ground-engageable legs, a pair of end walls projecting upwardly above said frame at the opposite ends thereof, a pair of collapsible sidewalls extending along the sides of said crib, each of said sidewalls comprising a peripheral frame supporting a sheet of flexible material, at least one of said sidewalls being swingably mounted on said crib for swinging movement about a horizontal axis between an extended position in which the uppermost longitudinally extending edge of said sidewall is disposed substantially above the plane of said spring-supporting frame and a collapsed position in which said longitudinally extending edge is disposed adjacent the plane of said spring-supporting frame whereby the upwardly presented face of a mattress which may be supported on said spring-supporting frame will be disposed above the plane of said longitudinally extending sidewall edge, and means adjacent 20

the upper end of at least one of said end boards and said longitudinally extending sidewall edge releasably interconnecting said one of said end boards with said one of said sidewalls when said one of said sidewalls is in its extended position.
